FENCE TOOL

Albert P. Cox, Young, Ariz., assignor of one-half
to Jeff McInturff, Young, Ariz.

Application April 18, 1933. Serial No. 666,754

1 Claim. (Cl. 140—102.5)

This invention relates to a novel wire fence tool of a diversified type which may be used to all practical purposes in a number of different ways, such as for example, a wire tightener, a slack take-up implement, a wire splicer, and a staple puller.

In perfecting the preferred embodiment of the invention, I have evolved and produced a simple, economical, and expeditiously usable tool which is extremely handy for fence repair purposes, and which is otherwise satisfactorily constructed to fulfill the requirements of the user to the end that it has received unqualified endorsement by the trade.

Although the invention does not enter a wholly new or uncultivated field of endeavor, it embraces unique features which I believe render it more adaptable for the purposes intended and characterize it as a worthy contribution to this particular classification of invention.

Other features and advantages will become more readily apparent from the following description and drawings.

In the drawings:

25 Figure 1 is an elevational view showing the manner in which the tool is initially placed for slack take-up purposes and as a subsequent wire stretcher.

Figure 2 represents the second step in the 30 operation.

Figure 3 represents the final eye-forming step wherein the eye may be thereafter utilized for convenient longitudinal drawing of the entire wires to enable it to be satisfactorily stapled to a post.

Figure 4 is a view showing the initial position of the tool when employed for wire splicing or repair purposes.

Figure 5 is a view similar to Figure 4 showing 40 the second step in the operation.

Figure 6 illustrates the final step in this repair operation, and,

Figure 7 is a perspective view of the tool on a slightly enlarged scale.

45 As shown in Figure 7, the tool is generally distinguished by the numeral 8. It is of appropriate proportion and preferably made from a sturdy iron rod 9. One end of the rod is formed with a loop 10 which serves as a handle as well as an adapter element to accommodate a separate implement to be used as a handle for twisting and turning the tool.

The opposite end portion is bent at right angles as indicated at 11 and tapered to form a 50 hook. This may be used as a staple puller and

used as shown in Figures 1 and 2 for slack take-up and wire stretching purposes. The intermediate portion of the rod is flattened as indicated at 12 and then provided with a longitudinally elongated slot 13. This constitutes a winding 60 and reeling mandrel.

Referring now to Figures 1 to 3 inclusive wherein it will be observed that the tool is used for slack take-up and wire stretching purposes, I first call attention to Figure 1. Here the hook 65 11 is engaged over a loose wire 14. The tool and hook is so manipulated in an obvious manner as to form an eye 15 as shown in Figure 2 which eye is twisted the requisite number of turns or convolutions as indicated at 16 in Figure 3. The 70 formation of this eye takes up limited slack in the wire itself. The eye also provides means whereby the tool can be temporarily and securely attached to the wire to pull it longitudinally and to allow it to be fastened on a post (not shown). 75 In other words, it facilitates initial stapling or re-stapling of an old loose wire after it has been stretched by using the tool in the manner described.

In using the tool for fence-wire repair or splicing purposes, it is employed as illustrated in Figures 4, 5 and 6. Attention is now invited to Figure 6 wherein it will be observed that one free end portion of the wire is distinguished by the numeral 17 this being formed into a loop 18 by 80 twisting the extremity of the wire as indicated at 19 and using pliers or the like for the purpose.

The complementary wire is denoted by the numeral 20 and this has its free end also formed with a corresponding loop 21. The inserted or 85 repair wire 22 is preferably of an easily bendable or flexible character, but must, of course, possess requisite strength. Here again, one end of the wire 22 is formed with a loop as at 23 attached to the first loop 18 thereby connecting the two 90 wires 17 and 22 together. Then the free end or right hand end portion of the wire 22 is drawn through the remaining loop 21 and cut off to the desired length, allowing for final fastening of the wire-end.

The free end of the wire 22 is drawn through the loop 21 and then passed through the slot 13 in the flat mandrel portion 12 of the tool. Then the tool is rotated axially to twist or coil the wire around the mandrel as indicated at 23. 105 This draws the two wires 17 and 20 together from the position shown in Figure 4 to the position shown in Figure 5. Then the tool 8 is turned around the wire 22 so as to twist the wire-ends as indicated at 24 in Figure 6. Consequently the 110

repair wire 22 is thus inserted and securely anchored in place.

The looped end 12 of the tool serves as a handle as before stated, and also as a retention element for an individual implement or tool which may be necessary in twisting and turning the tool in places where the wire is of stout formation.

Particular emphasis is placed on the flat hammered central portion 12 defining the so-called mandrel or shaft on which the wire is wound as indicated at 23 in Figure 5. This flattened portion is of a predetermined portion and aids considerably in coiling the wire as well as twisting it around itself as indicated in Figure 6. Moreover, it permits uncoiling of the remaining portion of the wire so that the tool can be detached. The elongated slot 13 provides a convenient means for anchoring or attaching the extremity 20 of the wire 22 to the tool to start the reeling operation.

A careful consideration of the foregoing description in conjunction with the illustrative drawings will enable the reader to obtain a clear understanding of the purpose, features and advantages, the explicit construction, and the invention as hereinafter claimed.

It is to be understood that minor changes in shape, size, relative proportions, and materials may be resorted to in practice without departing from the spirit of the invention or the scope of the invention as now claimed.

I claim:

In a tool of the class described, a one-piece bar of elongated form having the intermediate portion thereof flattened to form flat, wire engaging sides, said flat intermediate portions being formed with an elongated wire receiving slot opening out through said flat sides for the passage of a length of wire, the end portions of said elongated bar being free for manual engagement.

ALBERT P. COX.
